UNITED STATES PATENT OFFICE.

HECTOR LE DOUX, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

HEAD-MOTION FOR LOOMS.

1,164,104.

Specification of Letters Patent.

Patented Dec. 14, 1915.

Application filed May 14, 1915. Serial No. 28,181.

To all whom it may concern:

Be it known that I, HECTOR LE DOUX, a citizen of the United States, residing at Worcester, in the county of Worcester and State of Massachusetts, have invented a new and useful Head-Motion for Looms, of which the following is a specification.

This invention relates to a head motion for looms and particularly to certain improvements in a head motion of the well known "Knowles" type by which this head is better adapted to the production of fabrics of the "leno" type. In the weaving of this type of fabric the so-called "cross-over" harness is normally maintained in the lower shed at every pick but is necessarily raised to mid-position between successive picks whenever the crossing of the leno warp threads is changed. In some classes of goods it is desirable to bring the cross-over harness to mid-position at each beat of the lay in order to relieve the strain upon the leno warp threads during the beating-up operation.

It is the object of my invention to provide improved and simplified mechanism for thus bringing the cross-over harness to mid-position and for thereafter permitting the harness to return to its normal or lower position.

My invention further relates to certain devices, arrangements and combinations of parts which will be hereinafter described and more particularly pointed out in the appended claims.

A preferred form of my invention is shown in the drawings, in which,

Figure 1 is a side elevation of a head motion having my improvement embodied therein, certain of the parts being shown in section; Fig. 2 is a view similar to Fig. 1 but showing certain of the parts in a different position; Fig. 3 is a view similar to Figs. 1 and 2 but showing the parts in an intermediate position, and Figs. 4 and 5 are plan and sectional views respectively of a fancy leno fabric, for the weaving of which my invention is well adapted.

Referring to Fig. 1 I have shown my improved head motion mounted on a frame 10 which in turn is supported upon the loom arch 11. The frame 10 carries the usual upper and lower cylinder gears 12 and 13 rotatable on fixed bearings and provided with suitable driving connections (not

shown) through which they are continuously rotated in the directions indicated. A vibrator gear 14 for each harness jack 15 is rotatably mounted upon a vibrator lever 16 pivoted upon a fixed stud or shaft 17 and controlled in its vertical position by pattern rolls 18 carried by a pattern chain 19. The pattern chain may be actuated and controlled by any of the devices usually provided for this purpose. Each jack 15 is pivoted to the loom frame at 20 and is attached by a flexible connection 21 to a rocking plate 22 pivoted to the loom arch at 23. The plate 22 is also connected through a strap or other flexible member 24 to a harness 25 of the usual construction. The jack 15 is moved angularly in opposite directions about its pivot 20 by a link 26 pivotally connected at one end to the jack 15 and at the opposite end to the vibrator gear 14. As the vibrator gear is given alternate partial rotations in opposite directions the jack 15 will be moved from the position shown in Fig. 1 to that shown in Fig. 2 and vice versa. An auxiliary harness jack 30 is pivoted at 31 to an upwardly projecting arm 32 rigidly secured to the loom arch 11. At its upper end the jack 30 is provided with a series of holes each adapted to receive a connection from the jack to a rocking plate 220 which in turn is connected through a strap 240 to the cross-over harness 250, these connections being substantially the same as the connections from the jack 15 to the harness 25. The downwardly extending arm 33 of the auxiliary jack 30 is adjustably connected by a link 33 to the upwardly extending arm 34 of a bell crank lever 35 which is pivoted to the loom frame at 36. The horizontally extending arm 37 of the bell crank 35 is provided with a downwardly extending projection 38 positioned to engage a cam surface 39 formed upon the upper edge of the vibrator link 26. The projection 38 is held in engagement with the cam surface 39 by a coil spring 40 encircling a rod 41 pivoted at its lower end to the arm 37 of the bell crank 35 and having its upper end guided through a projection 42 carried by the loom frame. The spring 40 is positioned between the arm 37 and the projection 42 and acts to force the arm yieldingly downwardly. The cam surface 39 is so formed that movement of the link 26 in either direction will raise the arm 37 of the

bell crank 35, thus actuating the auxiliary jack 30 through the medium of the link 33 and raising the cross-over harness 250 to mid-position, as shown in Fig. 3. As the 10 link 26 completes its movement in the same direction, the harness 250 is permitted to return to its normal lower position, such movement of the harness being accomplished by spring devices (not shown) connected to the lower portion of the harness.

15 The angular movement of the rock plate 220 may be varied by changing the point of attachment of its connection to the auxiliary jack 30 or by changing the point of connection of the link 33 to the arm 34.

20 While I have shown the left hand end of the link 26 as supported and guided by the jack 15, it will be evident that this connection of the link and jack is not necessary for the operation of the auxiliary jack. If a 25 separate vibrating gear and link is provided for actuating the auxiliary jack the left hand end of the link may be movably guided in any convenient manner and not necessarily as shown in the drawings.

30 In Figs. 4 and 5 I have illustrated one of the many types of fabrics for the weaving of which my improvements are adapted. In these figures the ordinary warp threads 35 are indicated at W, the leno warp threads at L and the filling or weft threads at F. The number of picks of filling inserted between each two crossings of the leno threads, also the relative lateral arrangement of the leno threads with reference to the warp may of course be varied as desired.

40 Having thus described my invention it will be evident that changes and modifications can be made therein by those skilled in the art without departing from the spirit and scope thereof as set forth in the claims and I do not wish to be otherwise limited to the details herein disclosed, but

45 What I do claim is:—

1. In a head motion for looms, in combination, a pattern-controlled vibrator lever, an intermittently-movable vibrator gear carried thereby, a link pivotally connected at one end to said gear and having its opposite 50 end movably supported, said link having a cam surface formed thereon, a lever engaged by said cam surface, an auxiliary harness jack, and connections from said lever to said jack.

55 2. In a head motion for looms, in combination, a pattern-controlled vibrator lever,

an intermittently-movable vibrator gear carried thereby, a link pivotally connected at one end to said gear and having its opposite end movably supported, said link having a 60 cam surface formed thereon, a lever mounted on a fixed pivot and engaged by said cam surface, a spring to force said lever against said cam surface, an auxiliary jack, and connections from said lever to said auxiliary jack.

3. In a head motion for looms, in combination, a pattern-controlled vibrator lever, an intermittently-movable vibrator gear carried thereby, an auxiliary harness jack, a 70 cam movable with said vibrator gear, connections from said cam to said jack, whereby said cam is effective to move said jack positively in one direction, and a spring connected to move said jack yieldingly in the 75 opposite direction.

4. In a head motion for looms, in combination, a pattern-controlled vibrator lever, an intermittently-movable vibrator gear carried thereby, a harness jack, a link connect- 80 ing said jack to said vibrator gear, a cross-over harness, an auxiliary jack mounted upon a fixed pivot and connected to said cross-over harness, a lever also mounted upon a fixed pivot, and connections between 85 said lever and said auxiliary jack, said link having a cam surface formed thereon effective to actuate said lever and said auxiliary jack to raise said cross-over harness as said vibrator gear is partially rotated in either 90 direction.

5. In a head motion for looms, in combination, a pattern-controlled vibrator lever, an intermittently-movable vibrator gear carried thereby, a harness jack, a link connect- 95 ing said jack to said vibrator gear, a cross-over harness, an auxiliary jack mounted upon a fixed pivot and connected to said cross-over harness, an actuating lever also mounted upon a fixed pivot, connections between 100 said lever and said auxiliary jack, said link having a cam surface formed thereon effective to move said auxiliary jack and cross-over harness positively to mid-position whenever said vibrator gear is partially 105 rotated in either direction, and means to vary the movement of the harness relatively to the movement of the actuating lever.

In testimony whereof I have hereunto set my hand.

HECTOR LE DOUX.
